UNITED STATES PATENT OFFICE

2,005,479

LOCK LID FOR JOURNAL BOXES

Alfred C. Schmehl, Beaver Falls, and John P. Anderson, Koppel, Pa.

Application January 17, 1929, Serial No. 333,077

5 Claims. (Cl. 308—51)

An object of our invention is to provide a means for locking the lid of a railway car journal box in a closed position to prevent theft of the journal brasses.

5 Another object of our invention is to provide a locking lid which may be applied to a railway car journal box and be locked in closed position.

10 A further object of our invention is to provide a locking mechanism which cannot be unlocked by use of the fingers and which requires a specially formed tool for operating.

15 Referring to the drawing, Fig. 1 is a plan view of a journal box lid embodying one form of our invention; Fig. 2 is a section taken along the lines 2—2 of Fig. 1; Fig. 3 is a plan view of a journal box lid embodying a modification of our invention; Fig. 4 is a section taken along the lines 4—4 of Fig. 3.

20 Referring now in detail to the drawing where like reference characters refer to like parts, reference character 1 indicates a portion of the journal box, as shown in dot and dash lines on Figs. 1 and 2; reference character 2 indicates the journal box lid which is hinged to one side of the box 25 in the usual manner.

25 Formed integral with the lid 2 is a housing 3 which contains the lid locking mechanism comprising a rotatable member 4 suitably mounted in the walls 5 of the housing 3. Suitably formed portions of the member 4 engage with the walls 5 and prevent displacement of that member from its mountings while permitting free rotation on its longitudinal axis. A box engaging member 6 is mounted on the member 4, and has the portion 30 thereof in contact with the member 4 formed with suitable threads to engage with the corresponding threads 7 of the member 4. The walls 5 form stops which limit the movement of the member 6 longitudinally of the member 4. At 35 one end of the member 4 and accessible from the exterior of the box through the opening 8 in the housing 3 is a suitably formed head 9 by means of which the member 4 may be rotated. It will be noted from an inspection of Figs. 1 and 2 that the head 9 of the member 4 is wholly contained within the opening 8 of the housing 3 and that the space between the head 9 and walls of the housing is not sufficiently large to permit the insertion of the fingers. In order to turn the member 4 a specially formed tool must be used which is sufficiently small to enter the opening 8 and having a suitably formed opening for engaging with the head 9 of the member 4.

40 Within the housing 3 and at the side of the box 45 at which the lid is mounted is a resilient member

5 which has one end in engagement with the lid and the other end adapted to engage with a portion of the box when the lid is mounted thereon; Figs. 1 and 2 show in full lines the position of the member 5 when the lid is free of the box and in dot and dash lines the position assumed by the member 5 when the lid is mounted on the journal box and the member 5 is in engagement with the portion 11 of the box. This displacement of one end of the resilient member 5 causes the lid to remain open when unlocked and by so doing assists in bringing to the attention of the operator the fact that the box lid is unlocked.

50 When the lid is in closed position and the special tool is inserted through the opening 8 of the housing 3 and in engagement with the head 9 of the member 4, by turning the member 4 in one direction the member 6 is moved into engagement with the portion 12 of the journal box and when turned in the opposite direction is moved out of engagement with the box. In this manner the lid can be closed and the member 6 moved into engagement with the journal box, locking the lid in a closed position. The lid cannot be then 55 unlocked or opened accidentally until the member 4 is turned as previously stated.

55 Figs. 3 and 4 show a modification of my invention in which reference character 13 indicates a portion of a journal box as shown in dot and dash lines, having a lid 14 hinged at one side thereof in the usual manner. A housing 15 is formed integral with the lid and contains the locking member 16 and lock operating member 17. At one end of the housing 15 is a resilient member 18 which engages with a portion 19 of the journal box to cause the lid to remain in opened position when unlocked. The locking member 16, as shown in Figs. 3 and 4, is tiltably mounted within the housing 15 and has a portion 20 which engages with the box when the lid is locked in position. At the opposite end from the portion 20 of the member 16 is an enlarged portion 21 which is heavier than the portion 20 and which causes the member 16 to 40 tilt on its support to a position in which the portion 20 is free of the journal box unless engaged by the lock operating member 17. The lock operating member 17 is threaded for a portion of its length and is mounted in the wall 22 of the housing 15. One end of the member 17 has a suitably formed head by means of which the member can be turned to advance or withdraw the member into or out of contact with the member 16. At the other end of the member 17 is 45 50 55

a stop 23 which prevents the member from being removed from the housing. The head of the member 17 is wholly contained within the housing 15 and is accessible from the exterior of the box 5 through the opening 24 of the housing. As in the case of Figs. 1 and 2 the opening 24 of the housing is too small to permit the insertion of the fingers to turn the lock operating member 17. With the lid held in closed position the member 17 is turned so as to move inwardly and tilt the member 16, bringing the portion 26 into engagement with the journal box and locking the lid in closed position. The member 17 when turned in opposite direction moves out of contact with the member 16 and the portion 21 of that member being heavier than the box engaging portion moves downward by gravity and freeing the member 16 from the box and the lid can then be opened.

20 Having thus described the invention what we claim as new and desire to secure by Letters Patent is:

1. The combination in a journal box having an opening in its front wall, of a lid pivoted 25 to the box and adapted to close the opening, a latch pivotally mounted on the lid and normally inoperative when the lid is moved to closed position and a member mounted on the lid independent of the latch and adapted for advancement into the box to move the latch into operative position.

2. The combination in a journal box having an opening in its front wall, of a lid for closing the opening, a member movably mounted on the 35 inner face of the lid for engagement with a wall of the box, a rotatable member mounted on the lid in spaced relation to the mounting of the first named member, and adapted when rotated to move and hold the first member in engagement with the box.

40 3. In a journal box, in combination, a hollow body portion, a lid, a housing on the lid having an open side adjacent the outer opening of the box and a depending end wall closing the housing, a screw threaded member projecting through said

5 wall and within the housing, a projection on the housing forming a restricted opening and affording access to the screw threaded member, and a latch mounted within the housing, operatively associated with the screw threaded member and releasably engaging the said body portion upon manipulation of the screw threaded member.

4. In a railway car journal box, in combination, a hinged lid forming a cover for the box, a housing on the lid having an open inner side communicating with the interior of the box, a depending wall preventing access to the box through the housing, an opening in the wall and a screw threaded member disposed in said opening, means on said screw threaded member co-operating with said wall to restrict movement of the screw threaded member in a direction longitudinally of its axis, a latch mounted within said housing and projecting into the box when the lid is in closed position, said latch and screw threaded member being operably associated so as to move the latch into and out of engagement with the interior of the box upon rotation of the screw threaded member, a projection on said housing extending below said depending wall 25 forming a restricted opening, the screw threaded member having its outer portion extending beyond the depending wall of the housing and within the restricted opening.

5. In a lock lid for a journal box, a housing including an end wall formed on the lid, a screw threaded member secured within the housing, in a position to be rotatable upon a longitudinal axis and restricted in movement longitudinally of said axis, a latch member within the housing and upon the said member, internal threads on the latch engaging the screw threaded member so as to move longitudinally thereof as the said member is rotated, a projection on said lid extending below the said end wall to form a restricted opening, one end of said screw threaded member projecting through said end wall and within the opening.
